Assistant Examiner — Christopher John Suarez La Rosa

(57) CLAIM

The ornamental design for a card wallet as shown and described.

DESCRIPTION

1. Card wallet

1.1 : Perspective

1.2 : Front

1.3 : Back

1.4 : Left

1.5 : Right

1.6 : Top

1.7 : Bottom

1.8 : Reference view showing open position

The thin broken lines represent stitch lines and form part of the design; the product can be attached to a phone case; the reference view (fig. 1.8) shows the subject design in its open position.

1 Claim, 8 Drawing Sheets
